(57) **CLAIM**

The ornamental design for a display screen portion with icon, as shown and described.

DESCRIPTION

The present application is related to U.S. Design patent application Ser. No. 29/623,813, U.S. Design patent application Ser. No. 29/623,844, U.S. Design patent application Ser. No. 29/623,815, U.S. Design patent application Ser. No. 29/623,826, and U.S. Design patent application Ser. No. 29/623,833, filed Oct. 27, 2017, the entire disclosures of which are incorporated herein by reference.

The file of this patent contains at least one drawing/photograph executed in color. Copies of this patent with color drawing(s)/photograph(s) will be provided by the Office upon request and payment of the necessary fee.

The FIGURE is a front view of a display screen portion with icon, showing the new design.

The dash-dot broken lines showing the display screen portion depict the bounds of the claimed design and form no part thereof. In the FIGURE, the perimeter of the portion of the underlying display screen and the graphical interface are understood to be flush.
